UNITED STATES PATENT OFFICE.

LEO E. KLAUSNER, OF NEW YORK, AND MORRIS SKLOVER, OF BROOKLYN, NEW YORK.

MEANS FOR DISPENSING LENS-CLEANING CLOTHS.

Application filed April 2, 1926. Serial No. 99,228.

The object of our invention is the provision of simple but effective means whereby a single lens cleaning cloth especially adapted to the cleaning and polishing of eyeglass and 5 spectacle lenses may be positively, conveniently and expeditiously separated from the bottom of a pile of such cloths contained in a suitable receptacle, and rendered available for immediate use as hereinafter fully set 10 forth, the invention consisting in the specific construction, combination and arrangement of parts described and claimed, whereby these and other advantageous results are attained.

15 In the accompanying drawings we illustrate a practical embodiment of the essential features of our invention as incorporated in apparatus for the storage, segregation and delivery of lens cleaning and polishing cloths 20 of the character designated, although we do not limit ourselves to the identical form and construction of component parts shown by way of exemplification, since changes may be made in minor details, and equivalent 25 mechanical expedients resorted to with like results, and without departing from the spirit and intent of our invention in this respect.

With this understanding:—

30 Fig. 1, represents an isometrical view of our cloth dispenser, the cover being broken away in part;

Fig. 2, is a vertical sectional elevation taken upon plane of line 2—2, Fig. 1, with 35 the parts in normal relationship;

Fig. 3, is a view like unto Fig. 2, illustrating the relative positions of the parts at the completion of the rear movement of the selective and delivery mechanism;

40 Fig. 4, is an elevation of the underside of the device taken upon plane of line 4—4, Fig. 2, with the operative parts in normal positions, as in said Fig. 2;

Fig. 5, is a similar elevation taken upon 45 plane of line 5—5, Fig. 3, with the operative parts in the positions shown in said Fig. 3;

Fig. 6, is a sectional detail taken upon plane of line 6—6, Fig. 4, but upon a larger scale, illustrating the inception of the lower 50 cloth detaching operation;

Fig. 7, is a view like unto Fig. 6, illustrating a phase in the detaching operation just subsequent to that shown in Fig. 6;

Fig. 8, is a sectional detail taken upon 55 plane of line 8—8, Fig. 5, but on the same scale as Figs. 6 and 7, and illustrating the

completion of the cloth detaching operation;

Fig. 9, is a sectional detail taken upon plane of line 9—9, Fig. 2;

Fig. 10, is a top view of our cloth dispensing apparatus, with the cover removed, and minus the lens cleaning cloths;

Fig. 11, is a sectional elevation on plane of line 11—11, Fig. 10, but on a larger scale;

Fig. 12, is a perspective view of the release 65 plate;

Fig. 13, is a view of the cloth detachment plate;

Fig. 14, is a perspective view of the serrated starter frame; and

Fig. 15, is a perspective view indicating a 70 form of lens cleaning cloth adapted for use in our dispensing apparatus.

The casing C, of our dispenser is rectangular in general configuration, its upper 75 portion being formed with a transverse partition C', separating the cloth compartment C², from the rear compartment C³, in which the release plate R, is located, the space below said compartments C', C², being for the 80 accommodation of the other operative parts of the device. C^x, is a cover plate for the exclusion of dust and extraneous objects.

The detachment plate D, is slidably supported between guide ways c, c, on the 85 sides of the casing C, and is held normally in retracted position by stops d, d, on its underside contacting with shoulders c', c', at the front of the casing, by means of retractile springs a, a, attached to a cross bar d', on the underside of the detachment plate D, and to fixed points c², c², on the inner side walls of the casing C, as shown more particularly in Figs. 2 and 3, of the drawings,—said cross bar d', being mounted 95 upon and between brackets d², d², and said cross bar d', also functioning as the pivotal support for the starter frame S.

A shoulder d³, on the forward part of the detachment plate D, limits the inward 100 thrust of said plate D, by contacting with the front walls of the cloth compartment C². Said detachment plate D, is formed with a medial transverse delivery slot d⁴, for the accommodation of the tooth bar s, of 105 the starter frame S, said tooth bar s, being rigidly attached to the side members s', s', of said frame S, as shown more particularly in Fig. 14, of the drawings, and said side members s', s', being extended rearward beyond 110 the pivotal rod d', of the frame, to constitute trip arms s², s², which, by con-

tacting with fixed trip shoulders c^3 , c^3 , on the lower edge of the partition C' , rock said starter frame S , forward and upward with its tooth bar s , protruding into said 5 transverse slot d^4 , in the detachment plate D .

The front edges of the lowest cleaning cloth k , to be dispensed rest upon a series of spaced apart shoulders c^4 , c^4 , on the lower 10 edge of the front wall of the cloth compartment C^2 , the spaces between said shoulders c^4 , c^4 , being for the accommodation of the teeth of the bar s , of the starter frame; and the rear edge of said lower cleaning cloth k , 15 of the pile thereof in the cloth compartment C^2 , rests upon the forward edge r , of the release plate R , as shown more particularly in Fig. 11, of the drawings.

The release plate R , is attached to and suspended upon a flat spring r' , the upper end 20 of which is rigidly secured to the partition C' , said spring r' , tending normally to hold the release plate R , in advanced position with its forward edge r , under the rear edge 25 of the lowest cleaning cloth k , as before stated. In this position shoulders r^2 , r^2 , on the release plate R , rest against the lower edge of the partition C' , and thus limit the forward thrust of said release plate, as 30 shown in Figs. 2 and 10.

f , f , are twin spring stripping fingers mounted on the forward end of a bracket F , attached to the rear wall C^1 , of the casting C , below the release plate R , and below 35 the path of the detachment plate D . The normal position of these stripping fingers (i. e. when the operative parts are at rest) is shown in Fig. 4. During the rearward thrust of the detachment plate D , pin d^5 , d^5 , 40 on the underside of the latter contact with said stripper fingers f , f , and force them back into the positions indicated in Fig. 5, just prior to the completion of said rearward thrust of the detachment plate D , but 45 the completion of said movement carries the pins d^5 , d^5 , beyond the ends of said stripper fingers f , f , so that the latter then automatically spring forward and impinge 50 against the portion of the cloth k , adjacent to and protruding through the slot d^4 , as illustrated in Fig. 8, of the drawings,—the “kick” thus administered insuring the detachment of the rear edge of the cloth k , from the front edge r , of the release plate 55 R , and from the layer of cloths above, and thus preventing clogging.

Preferably a follower weight W , is placed upon the top of the pile of lens cleaning cloths k , deposited in the containing compartment C^2 , as indicated in Figs. 2 and 3, of the drawings.

Presuming the operative parts to be in normal relative positions, as in Figs. 2, 4, 60 10 and 11, at the inception of the rearward movement of the detachment plate D , under

hand pressure applied to the protuberant front portion thereof, the teeth on the bar s , of the starter frame S , cause the front edge of the lower cloth k , to assume a partial fold, as indicated at k' , Fig. 6, sufficient to cause said front edge of the cloth to clear the shoulders c^4 , on the front wall of the container C^2 . Next, as the rear movement of the detachment plate D , is continued, the trip arms s^2 , s^2 , on the starter frame S , clear 70 the trip shoulders c^3 , on the lower rear portion of the partition C' , thereby allowing the starter frame S , to turn by gravity on its pivotal support d' , the first result being indicated in Fig. 7, which shows the drop 75 of the front end of the cloth k , through the transverse slot d^4 , in the detachment plate D . As the rearward movement progresses the pins d^5 , d^5 , on the under side of the detachment plate D , engage with and push 80 back the stripper fingers f , f , and said detachment plate D , also contacts with the shoulders r^2 , r^2 , on the rear edge of the release plate R , thereby retracting the same 85 against the resistance of the suspender spring r' , and withdrawing the front edge r , of said release plate R , from beneath the rear edge of the cloth k , and simultaneously 90 releasing the stripper fingers f , f , and causing them to impinge against the rear edge 95 of the cloth k , as indicated in Fig. 8, to insure clearance thereof.

Upon the release of the detachment plate D , from hand pressure, the retractile springs 100 a , a , return all the operative parts to normal positions, ready for the dispensing of the next succeeding cloth k , at the bottom of the pile thereof in the container C^2 .

It is to be understood that the lens cleaning and polishing cloths k , are designed primarily for gratuitous distribution by opticians and others interested in the trade, and to function as advertising mediums.

What we claim as our invention and desire to secure by Letters Patent, is:—

1. Lens cloth dispensing apparatus of the character designated, comprising a cloth containing compartment, a slidable detachment plate arranged in connection therewith and formed with a transverse delivery slot, spaced apart cloth-supporting shoulders on the front wall of said cloth containing compartment, a slidable release plate adapted to the temporary support of the rear edges of the lens cloths, a starter frame pivotally supported on the underside of said slidable detachment plate and formed with a tooth bar for engagement with the lowest lens cloth in the said containing compartment, and retractile spring means tending constantly to maintain the operative parts in normal relative positions, substantially in the manner and for the purpose set forth.

2. Lens cloth dispensing apparatus of the character designated, comprising a cloth

containing compartment, a slidable detachment plate arranged in connection therewith and formed with a transverse delivery slot, spaced apart cloth-supporting shoulders on the front wall of said cloth containing compartment, a slidable release plate adapted to the temporary support of the rear edges of the lens cloths, a starter frame pivotally supported on the underside of said 10 slidable detachment plate and formed with a tooth bar for engagement with the lowest lens cloth in the said containing compartment, and retractile spring means tending constantly to maintain the operative parts 15 in normal relative positions, together with twin spring stripper fingers controlled by the said detachment plate, substantially in the manner and for the purpose set forth. 3. Lens cloth dispensing apparatus of the character designated, comprising a cloth containing compartment, a slidable detachment plate arranged in connection therewith and formed with a transverse delivery slot, spaced apart cloth-supporting shoulders 20 on the front wall of said cloth containing compartment, a slidable release plate adapted to the temporary support of the rear edges of the lens cloths, a starter frame pivotally supported on the underside of said 25 slidable detachment plate and formed with a tooth bar for engagement with the lowest lens cloth in the said containing compartment, and retractile spring means tending constantly to maintain the operative parts 30 in normal relative positions, together with twin spring stripper fingers controlled by the said detachment plate, substantially in the manner and for the purpose set forth. 4. Lens cloth dispensing apparatus of the character designated, comprising a cloth containing compartment, a slidable detachment plate arranged in connection therewith and formed with a transverse delivery slot, spaced apart cloth-supporting shoulders 35 on the front wall of said cloth containing compartment, a slidable release plate adapted to the temporary support of the rear edges of the lens cloths, a starter frame pivotally supported on the underside of said 40 slidable detachment plate and formed with a tooth bar for engagement with the lowest lens cloth in the said containing compartment, and retractile spring means tending constantly to maintain the operative parts 45 in normal relative positions, together with twin spring stripper fingers controlled by the said detachment plate, substantially in the manner and for the purpose set forth. 50
